UNITED STATES PATENT OFFICE

GEORGE B. CROUSE, OF WOODCLIFF, NEW JERSEY, ASSIGNOR TO CONNER CROUSE CORPORATION, OF NEW YORK, N. Y., A CORPORATION OF NEW YORK

APPARATUS FOR ENERGIZING AN AUDION CIRCUIT

Application filed January 19, 1928. Serial No. 247,952.

This invention relates to apparatus for energizing an audion circuit, and more particularly to a filter for use between a source of rectified current and a direct current load circuit such as the circuit or circuits of an audio amplifier.

The filter network is of the same general type and has the same suppression characteristic as the filter described in my copending application Serial No. 680,096, filed December 19, 1928.

An object of the invention is to provide a simple and economical filter which will effect the desired degree of suppression of alternating components present in a rectified current supply. A further object is to provide a filter network which will selectively suppress alternating components to the degrees required for energizing dissimilar audion circuits. A further object is to provide a filter of the Wheatstone bridge type and in which audion circuits requiring substantially pure direct current are arranged in an arm conjugate to a source of rectified current, while another audion circuit which requires less freedom from alternating components is non-conjugate to the source.

These and other objects of the invention will be apparent from the following specification, when taken with the accompanying drawing, in which the single view is a schematic diagram of one embodiment of the invention.

In the drawing numerals 1 and 2 identify the terminals for connecting the primary winding 3 of a transformer to an alternating current light or power system. The transformer has an iron core 4 and a secondary winding 5 which is tapped at the middle for connection in the usual way with a full wave rectifier 6. The usual buffer condensers 7 and 8 are connected across the sections of the secondary winding for eliminating radio frequency radiation. A condenser 9 is shunted across the leads 10 and 11 which pass the rectified pulsating direct current to the filter mesh.

The impedances of the filter mesh are arranged in the form of a Wheatstone bridge having conjugate pairs of terminals to which

the rectified current leads 10, 11 and certain of the audion circuits, respectively, may be connected. The arms A and B are formed by the pure resistances 12 and 13, respectively, the value of arm B being generally greater than 53 that of arm A. The balancing arm C is formed by the inductance 14 in series with the capacity 15, while arm D is formed by the inductance 16, the inductances being wound on a common core 17. 60

The bridge network is so designed that the ratio of the impedance of the inductance 14 minus the impedance of the condenser 15 to the impedance of the inductance 16 is equal to the ratio of the resistance 12 to the resistance 13 at the frequency of the most disturbing alternating component passed by the rectifier 6. The most disturbing component may or may not be the fundamental frequency, depending upon the frequency of the source of 65 alternating current and the type of rectifier employed. With a 60 cycle power supply and a full wave rectifier the bridge is preferably balanced for the 120 cycle fundamental, but with a 25 cycle power supply a more economical construction will usually be obtained 70 when the bridge is balanced for components of 150 cycle current. The network will not be perfectly balanced at other frequencies but the degree of unbalance may be made 75 negligibly small by making the impedance of the inductances 14, 16 relatively high in comparison with the impedance of the condenser 15. 75

For certain uses where substantially complete suppression of alternating components is required the effective resistance of the inductances 14, 16 must be considered, and the ratio of their effective resistances should be the same as the ratio of the resistances 12 80 and 13. The positive terminal 18 of the audion circuits is preferably adjustable through a small range for varying the ratio of arms 12 and 13 to correct for manufacturing variations. 85

The direct current output terminals 18, 19 are connected by an alternating current path comprising in series the resistances 20, 21 and the condenser 22 which connects the outer ends of the resistances. Leads are connected 90 95 100

to the outer and inner ends, respectively, of the resistance 20 for supplying plate current to the audions of the detector and of the amplifier stages, except the power amplifier, respectively. On the drawing these leads are identified by the legends "DET" and "90 V", respectively. The outer end of resistance 21 is connected by the lead "—B" to the lower plate terminal of the radio receiver, and leads 10 "—C 4½" and "—C 40" connect an intermediate point and the inner end of the resistance 20 to appropriate terminals on the radio receiver for supplying grid bias voltages. By-pass condensers 23, 24 are connected between the bridge terminals 18, 19, respectively, and the —B lead.

The plate voltage to be applied to the audion of the power stage of the receiver does not require the degree of filtering which is essential in the preliminary stages, since any ripple effect in the output of the power stage is not further amplified. The plate circuit of the power stage may be connected by the lead "180 V" to the junction of inductance 14 and condenser 15 in the bridge arm C which lies between the positive source lead 10 and the negative direct current terminal 19.

It is to be understood that the network may be designed to deliver voltages of any desired magnitudes and that the use of legends such as "90 V" is not intended to limit the invention to apparatus supplying the particular voltages indicated by the several legends. When direct current power lines of appropriate voltage are available the transformer and rectifier may, of course, be eliminated as the direct current generators rectify the alternating current to deliver it to the power lines. The rectified current lead lines 10, 11 may be connected across the direct current power lines and the impedances of the bridge arms designed to effect a maximum suppression of the most disturbing alternating component by balancing the bridge at the frequency of that component.

It will be apparent that the invention is not limited to the specific construction illustrated in the drawings as various changes may be made without departing from the spirit of my invention as set forth in the following claims. The particular modification shown in the drawings is designed to supply plate and grid bias voltages, but it will be apparent that the same construction may be employed to supply filament and grid voltages by an appropriate choice of the impedances constituting the bridge network.

I claim:

1. In apparatus for energizing an audion circuit from a source of rectified current, a plurality of impedances arranged as an alternating current Wheatstone bridge across which said source and said circuit may be connected as conjugate arms, the impedances forming two adjacent arms being resistive,

and the other two arms comprising an inductance, and an inductance in series with a capacity, respectively.

2. In apparatus for energizing an audion circuit from a source of rectified current, a plurality of parallel paths connected across said source, one of said paths comprising a resistance and the other path comprising a pair of inductances connected to the respective terminals of said source and a capacity joining said inductances, the condenser terminal of one inductance and an intermediate point of said resistance serving as terminals for said audion circuit. 70

3. In a filter network for use between a source of rectified current and an audion circuit, a plurality of impedances arranged as an alternating current Wheatstone bridge network across which said source and said circuit are arranged as the conjugate arms thereof, a pair of adjacent bridge arms being resistive impedances and the remaining pair of bridge arms each including an inductive impedance, the ratio of the impedances of said inductive impedances at the frequency 90 of an alternating component present in the rectified current being substantially the same as the ratio of the resistances of the said resistive impedances. 85

4. A filter network for use between a source 95 of rectified current and an audion amplifier, said network comprising a plurality of impedances arranged in an alternating current Wheatstone bridge and having a pair of input and of output terminals across which said source and said audion amplifier may be connected as conjugate arms, and a resistance having one end connected to the negative output terminal, whereby said resistance may provide a negative grid bias potential 100 when the audion filament is connected to the other end of said resistance. 105

5. In apparatus for energizing from a source of rectified current a pair of audion circuits having dissimilar voltage requirements, a plurality of impedances arranged as an alternating current Wheatstone bridge having input terminals for connection to said source and output terminals across which there is substantially no difference in 110 alternating current potentials, a resistance having an end connected to one of said output terminals, a second resistance having an end connected to the other output terminal, and means for connecting the audion circuits between spaced points on the respective resistances. 115

6. A filter network for use between a source of rectified current and a plurality of audion grid and plate circuits, and of the type comprising a plurality of impedances arranged as an alternating current Wheatstone bridge, characterized by the fact that between the audion circuit terminals of said bridge network there are serially arranged a resistance, 125 130

a capacity, and a second resistance, and means for connecting plate circuits of different voltage requirements to the resistance adjacent the positive audion circuit terminal, and

5 means for connecting grid circuit of different voltage requirements to the resistance adjacent the negative audion circuit terminal.

7. In apparatus for energizing a plurality of audion circuits from a source of rectified

10 current, a plurality of impedances arranged as a Wheatstone bridge having conjugate pairs of terminals for connection to said source and said circuits, respectively, and a path between said circuit terminals comprising a pair of resistances in series with and at opposite sides of a condenser, the condenser end of the resistance connected to the negative circuit terminal of the bridge serving as a common terminal for all of said circuits, and condensers between the respective circuit terminals of the bridge network and the said common terminal.

15 8. In apparatus for energizing a plurality of audion circuits from a source of rectified

20 current, a condenser and an impedance network adapted to be connected in parallel across said source, said network having a pair of output terminals across which one of said circuits may be connected, the impedances between said source and said output terminals being so proportioned and related that the network effects a maximum suppression at a finite frequency within the lower range of frequencies passed by said rectifier, and

25 30 means for connecting another audion circuit across a part of said network, the impedance between said rectifier and the said other circuit cooperating with said condenser to form a filter mesh.

35 40 9. In apparatus for energizing a plurality of audion circuits from a source of rectified current, a plurality of impedances arranged as a wheatstone bridge across which said source and one of said circuits are connected as the conjugate arms thereof, and means for connecting another of said circuits which requires less freedom from alternating current components across a portion of the bridge which is non-conjugate to said source.

45 50 10. The invention as set forth in claim 9, wherein said audion circuits has a terminal in common.

55 55 11. The invention as set forth in claim 9, in combination with a condenser shunted across said source, the bridge arm between the positive source terminal and the negative circuit terminal comprising in series an inductance adjacent said source terminal and a condenser adjacent said circuit terminal, the said other audion circuit being connected across said condenser.

In testimony whereof, I affix my signature.
GEORGE B. CROUSE.
